UNITED STATES PATENT OFFICE.

JOHN LOVE, OF CUSSETA, TEXAS.

IMPROVEMENT IN PLOWS.

Specification forming part of Letters Patent No. 135,829, dated February 11, 1873.

To all whom it may concern:

Be it known that I, JOHN LOVE, of Cusseta, in the county of Cass and State of Texas, have invented an Improved Plow-Stock, of which the following is a specification:

The invention consists in the mode of applying several plow-irons to the same plow-frame so that they may be conveniently fastened and adjusted relatively to each other, as hereinafter described.

Figure 1 is a side elevation. Fig. 2 is an end view; and Figs. 3, 4, 5, 6, 7, and 8 are detail views.

A represents the ordinary wooden frame of a plow-stock, which has the oblique slot *a* in the beam *A'*. B B are flat curved plates, which are perforated at several points, *b*, and rigidly attached to beam. C is the scraper; D, the pulverizer; and E, the furrow-opener; each provided with a shank, F, perforated at several points, *f*. The scraper C is fastened between the plates B B by a bolt passing through the front holes, and is made to reach to or slightly below the surface of the ground, while the pulverizer is bolted next thereto,

and the furrow-opener in the rear, both with their depths corresponding to the intended depth of furrow.

The scraper C moves the clods and stones off the surface, while the pulverizer lightens up the lower parts of ridge and enables the opener E to make a cleaner furrow.

G H are two different forms of scraper; I, a mold-board plow; J, a subsoiler; K, a coverer; and L, a root-cutter; all these plow-irons being provided with the transversely-perforated shank F to enable them to be easily applied to the plow-stock A.

Having thus described my invention, what I claim as new, and desire to secure by Letters Patent, is—

The subsoiler D, pulverizer C, and furrow-opener E, provided with long shanks F relatively adjustable through plates B B and long oblique slot of beam A', as and for the purpose set forth.

JOHN LOVE.
